UNITED STATES PATENT OFFICE.

CLAYTON D. COLLEY, OF COEBURN, VIRGINIA.

CARPET-MEASURING MACHINE.

1,162,752.

Specification of Letters Patent.

Patented Dec. 7, 1915.

Application filed September 16, 1913. Serial No. 790,057.

To all whom it may concern:

Be it known that I, CLAYTON D. COLLEY, a citizen of the United States, residing at Coeburn, in the county of Wise and State 5 of Virginia, have invented a new and useful Carpet-Measuring Machine, of which the following is a specification.

The device forming the subject matter 10 of this application is adapted to be employed for measuring strips of material, such as carpets, mattings, cloth and the like.

One object of the present invention is to 15 provide a measuring device of simple construction which may readily be mounted upon a supporting frame for pivotal movement and for sliding movement, the frame carrying suitable means for winding up the material into rolls and the measuring device being actuated by the material, as the 20 same is rolled up.

The invention aims to improve generally and to enhance the utility of, devices of that type to which the present invention appertains.

25 With the above and other objects in view which will appear as the description proceeds, the invention resides in the combination and arrangement of parts and in the details of construction hereinafter described 30 and claimed, it being understood that changes in the precise embodiment of the invention herein disclosed can be made within the scope of what is claimed without departing from the spirit of the invention.

35 In the drawings: Figure 1 shows the invention in perspective, the auxiliary frame being swung out away from the main frame; Fig. 2 is a perspective showing the measuring frame swung down into operative relation 40 with respect to the roll of material which is being measured; Fig. 3 is a fragmental longitudinal section of the frame which carries the measuring mechanism.

In carrying out the invention there is provided 45 a main frame 1 which may be of any desired form. The main frame 1 in the present instance is shown as comprising rear uprights 2 and front uprights 3. The uprights 2 are connected by a top bar 4 and by a bottom bar 5, the uprights 3 being connected by a top bar 6 and by a bottom bar 7. Intersecting braces 8 unite the uprights at the ends of the main frame 1.

In their rear edges, the rear uprights 2 55 are provided with notches 9, receiving rotatably, trunnions 10 formed on the ends

of a stock roller 11 provided with a notch 12 in which is located a prong 14, adapted to engage the material, so that the same, before the measuring operation is begun, 60 may be disposed in a roll indicated by the reference character 15. Journalled for rotation in the rear uprights 2 of the main frame 1 is a shaft 16, carrying a curved, depending, resilient brake shoe 17 which 65 is adapted to bear on the roll 15. A helical spring 18 surrounds the shaft 16 adjacent one end thereof, one end of the spring 18 being secured to the shaft 16 and the other end of the spring being secured to one of 70 the rear uprights 2. The function of the spring 18 is to rotate or rock the shaft 16, and thus press the brake shoe 17 yieldingly against the material which is disposed in the roll 15 on the stock roller 11. The roll 75 15 is thus prevented from unwinding, under the weight of the free end of the roll.

Extending between the front uprights 2 and located adjacent the top of the main frame 1 is a guide bar 19. One of the front 80 uprights 3 carries a projection 20 which is located adjacent the guide bar 19. The function of the projection 20 in connection with the guide bar 19 will be brought out hereinafter.

85 The front uprights 3 are provided in their forward edges and adjacent their lower ends with notches 21 engaged rotatably with trunnions 22 on a receiving roller 23 having a notch 24 in which is located a prong 25, 90 adapted to engage the free end of the roll of material indicated at 15, the construction being such that when the roller 23 is rotated, the material will be disposed in a roll 26 upon the member 23 as will be understood 95 best from Fig. 2. While the material is being disposed in the roll 26, the material is measured off by a mechanism which will be described hereinafter. One of the trunnions 22 of the receiving roller 23 is provided 100 with a gear wheel 27, meshing into a gear wheel 28 carried by a shaft 29, journaled in one of the front uprights 3, and in a bracket 30 which is secured to the said upright. The shaft 29 may be squared as indicated at 31, 105 terminally, to receive a key (not shown) and this key it is to be noted, may be applied to the end of the stock roller 11. That trunnion 22 of the receiving roller 23 which is provided with the gear wheel 27 is equipped 110 with a knob 32, whereby rotation may be imparted to the receiving roller 23, directly,

instead of through the medium of the shaft 29 and the intermeshing gear wheels 27 and 28.

The invention includes an auxiliary frame, denoted generally by the numeral 33. This frame 33 is shown in Figs. 1 and 2 in operative relation with respect to the main frame 1. The auxiliary frame 33 may be of any desired form, but in the present instance is shown as comprising parallel side bars 34, terminating at their upper ends in hooks 35 which are adapted to engage over the guide bar 19. The guide bar 19 preferably is located close enough to the top bar 6 so that the hooks 35 may not accidentally be disengaged from the guide bar. The hooks 35, however, can be disengaged from the guide rod 19 when the receiving roller 23 is removed and when the auxiliary frame 33 is 20 swung inwardly.

It will be seen that by the construction above described, the auxiliary frame 33 is mounted upon the guide bar 19, for sliding movement in the direction of the length of the receiving roller 23, and for pivotal movement in direction at right angles to the length of the receiving roller. The auxiliary frame 33, obviously, is so constructed that it may be assembled readily with a main or supporting frame of any sort provided with a guide bar 19 or its equivalent. The side bars 34 of the auxiliary frame 33 are connected by braces 36 and 37, the brace 37 being shown as provided with angularly disposed feet 38 which bear against the side bars. Journaled for rotation in the side bars 34 adjacent the lower ends thereof is a shaft 39 upon which is mounted a drum 40 provided with pins 40^a. At one end, the shaft 39 is provided with a head 41 whereby the shaft may be rotated manually, if desired, although, in the ordinary operation of the structure, rotation is imparted to the shaft 39 when the teeth 40^a of the drum 40 are engaged with the roll 26 of material on the receiving roller 23. Reverse rotation of the shaft 29 is prevented by means of a ratchet wheel 42 mounted on the shaft, as shown in Fig. 3, the ratchet wheel 42 coating with a pawl 43 mounted on one of the side bars 34, the pawl being

actuated by a spring 43^a also secured to the said side bar. A meter 44 is carried by the auxiliary frame 33 and is operatively connected with the shaft 39.

In practical operation, the stock is assembled with the stock roller 11 and is led beneath the brake shoe 17 and is caught upon the prong 25 of the receiving roller 23. The auxiliary frame 33 is then disengaged from the projection 20 on the front upright 3 and is permitted to drop until the teeth 40^a of the drum 40 are engaged with the material in the roll 26, the meter 44 being set at zero. When the material is wrapped about the receiving roller 23, the drum 40 will be rotated, motion being transmitted to meter 44. The finger 72 serves to indicate the point at which the material is to be cut off.

It is to be observed that the auxiliary frame 33 may be slid to any position along the guide rod 19, and upon occasion may be lifted up and interengaged with the projection 20 as shown in Fig. 1, to permit the measured length of material to be cut off.

Having thus described the invention, what is claimed is:

In a device of the class described, a main frame comprising a top bar; a guide rod disposed below the top bar; a receiving roller journaled in the frame and mounted removably in the frame, the receiving roller being located below the guide rod; an auxiliary frame having hooks receiving the guide rod, the guide rod being located sufficiently close to the top bar so that the hooks can be detached from the guide rod only when the receiving roller is removed and when the auxiliary frame is swung inwardly; a meter carried by the auxiliary frame; and meter actuating means on the auxiliary frame, the meter actuating means coacting with the receiving roller.

In testimony that I claim the foregoing as my own, I have hereto affixed my signature in the presence of two witnesses.

CLAYTON D. COLLEY.
